[57] CLAIM

The ornamental design for an ash pan, as shown and described.

DESCRIPTION

FIG. 1 is a perspective view of an ash pan which embodies my design;

FIG. 2 is a front elevational view thereof, the rear elevational view being a mirror image thereof;

FIG. 3 is a right-side elevational view thereof, the left-side elevational view being a mirror image thereof;

FIG. 4 is a top plan view thereof;

FIG. 5 is a bottom plan view thereof; and,

FIG. 6 is a perspective view of the ash pan employed as part of an ash urn.

The broken line showings in the drawing figures are for illustrative purposes only and form no part of the claimed design.
